[57] CLAIM

The ornamental design for an endless belt for a track vehicle, as shown and useful on a heavy duty vehicle.

DESCRIPTION

FIG. 1 is a right side elevational view of an endless belt for a track vehicle embodying our new design;
FIG. 2 is a left side elevational view thereof;
FIG. 3 is a top plan view thereof;
FIG. 4 is a bottom plan view thereof;
FIG. 5 is a front elevational view thereof;
FIG. 6 is a rear elevational view thereof; and
FIG. 7 is a sectional view thereof taken along section lines VII-VII in FIG. 1.

FIG. 2

FIG. 5

FIG. 6

FIG. 7
